RIBBON FEED MECHANISM FOR
MANIFOLDING MACHINESRobert W. Ritzert, Dayton, Ohio, assignor to The
Egry Register Co., Dayton, Ohio, a corporation
of Ohio

Application April 28, 1943, Serial No. 484,813

2 Claims. (Cl. 197—153)

1

The present invention relates to manifolding machines, and in particular to such machines which are adapted to make multiple copies of typed or printed material by means of copying ribbons or carbons, particularly those machines used in connection with typing, adding and tabulating machines and the like.

In a typical prior art machine over which the present machine represents an improvement, the manifolding attachment is constituted of a framework carrying rollers over which the required number of paper sheets are fed upwardly from the typing or printing platen of the main machine and the finished copies are received in their basket or carrier at the rear of the machine.

The multiple typing or printing effect is provided by a plurality of carbon ribbons or webs which are interleaved between the paper sheets at the position of the platen. These ribbons are caused to move across the paper, i. e., normal to the movement of the paper, during the spacing line interval by means of a pin wheel drive. Thus the carbon ribbons are moved from one side of the paper to the other side in steps corresponding to the line spacing operations of the main typing machine, the separate movements of the ribbons ranging between one-quarter and one-half inch.

However, when the last line has been typed or printed on the paper, an automatic ejection mechanism is brought into play to move the entire group of paper rapidly upwardly over a considerable distance such that the succeeding sheet of the multiple group of paper lengths is placed in position for the next typing or printing operation. During this ejection spacing feeding operation of the paper webs, the pin wheel which feeds the carbon ribbons across the paper is rotated a plurality of times in order to effect a plurality of steps of movement of the copying ribbons. This quick and sustained movement of the carbon ribbons during the paper ejection operation serves to overcome any tendency for the carbon ribbon to stick to the paper during the time that the paper is moved rapidly across the ribbon. However, a manifolding machine of this type is designed to accommodate paper webs or sheets which are fed to the machine from a folded condition which obviously leaves creases or folds extending across the paper at positions which represent the upper and lower limits of the length of each paper web.

It has been found that notwithstanding the tendency for the pin wheel mechanism to pre-

2

vent sticking or adhesion of the carbon ribbon to the paper during the normal line spacing operation, this provision is not entirely satisfactory during the paper eject operation due to the fact that the carbon ribbons are tightly interleaved between the paper webs at the typing position and during this eject operation the folds of the paper must necessarily cross the carbon ribbons, causing these folds to carry the carbon ribbons with them as the paper is moved upwardly into the receiving basket.

In view of the fact that the paper webs move very quickly during this eject operation and over a considerable distance sufficient in order to position the next group of sheets as determined by the distance between the folds into the typing position, there is a tendency for the carbon ribbon to break. This tendency is enhanced in case the ribbon is of the paper rather than the cloth type but in any event this bowing-up effect on the ribbon represents a disadvantage in the efficient operation of the machine.

A number of different structures have been provided to reduce the tendency of the ribbons to break and these structures, for the most part, involve the feature of moving the ribbon during the eject operation to a position where there is considerable spacing between the paper webs and therefore away from the typing position where clamping effects are present. The present invention provides still another method and apparatus for preventing the breakage of the ribbons.

The latter are usually made of paper having a width slightly greater than the height of the type or other impression. These paper strips are fed from a plurality of spools, as many as there are ribbons, and the ribbons are interleaved with the paper webs. The ribbons are pulled across the webs by means of a pin wheel about which they are wound in stack form.

It has been found that when the paper is of excellent quality its strength is sufficient to guard against breakage except during the eject operation when the paper webs move across the carbon ribbons during the eject operation and the creases or folds in the paper tend to dig into the ribbons and thus carry them upwardly with the fast moving paper.

However, should the grade of the paper become inferior or if there are any dimensional weaknesses in the cross section of the paper, one or more lengths of the ribbon may break. Severe changes in atmospheric condition, such as humidity might enhance this tendency. Under

such conditions the ribbon would break even during the line spacing operation where difficulty on this score would not normally be present if the paper were of proper grade. The ribbons would most certainly break during the eject operation unless special apparatus is provided by which the ribbons are moved to a region in which there is considerable looseness between the ribbons and the paper webs.

Ribbons of this general character are automatic in operation in that when they have been initially set up to print or type and tabulate according to a certain form, and after the ribbons have been interleaved with the paper webs, the ribbons proceed to type or print without further supervision or assistance from the operator. One operator may have under his care a large number or battery of these machines and should one or more of the ribbons of any one of the machines break, it may be some time before this fact becomes known to the operator so that in the meantime much of the work is spoiled due to lack of the necessary carbon copies. This matter of carbon ribbon breakage is therefore a very important item.

The primary object of the invention is to increase the usable life of the ribbons or carbon coated strips which are employed in a multiple typing or printing machine.

Another object is to provide apparatus of a simple and inexpensive character to minimize and preferably to prevent the breakage of ribbons which are usually interleaved between the paper webs in a multiple typing or printing machine.

Still another object is to provide improved apparatus that will immediately detect the breakage of one or more lengths of the ribbon and will automatically signal the operator or will stop the entire machine.

The foregoing objects are obtained in brief by employing a double width ribbon in place of the single width and causing the ribbon to be positioned with respect to the typing position such that the type arms strike only one half the width of the ribbon and then is later re-fed through the machine in such a position that the type arms strike the other half of the ribbon. Thus both halves of the ribbon are employed for typing or printing purposes with consequent no waste in carbon surface and yet the ribbon will be considerably stronger than those used heretofore due to the double cross-sectional area. The breakage in the ribbon is detected in accordance with another feature of my invention by means of a tensioning determining device, or rather a device which indicates complete lack of tension as when the ribbon breaks.

The invention will be better understood when reference is made to the following description and the accompanying drawings in which:

Figure 1 represents a perspective view taken partly from the front and side of a typical form of typing, adding and tabulating machine improved in accordance with the present invention.

Figure 2 is an enlarged fragmentary view showing in elevation the various parts of the improvement and the manner in which these parts operate. This view illustrates that part of the machine which centers around the improved ribbon feeding and guiding mechanism.

Figure 3 is a longitudinal sectional view of the ribbon feeding and receiving spools, including the actuating mechanism. This section is taken approximately along the line 3-3 in Figure 1.

Figure 4 is an enlarged vertical sectional view taken through the multiple spool compartment and the ribbon breakage detecting apparatus. This view is taken along line 4-4 in Figure 1.

Figure 5 shows in the upper and lower views respectively the first typing level of the ribbon and the second typing level.

Figure 6 is a fragmentary detail view of the actuating mechanism and the winding and unwinding ribbon spools and showing the manner in which the rotation of the spools can be respectively reversed.

Figure 7 shows still another way in which the carbon ribbon of considerable width is caused to be typed thruout its entire area.

Referring more particularly to Figure 1 reference numeral 1 designates the main portion of the machine which may be power driven by means of a motor 2 and which may comprise any of the ordinary types of printing, typing, tabulating, and listing machines. There is a combined clutch and gear box 3 interposed between the motor 2 and the actuating element which drives the platen 4 of the machine. In order to accommodate the typing or printing on multiple lengths of paper, a manifolding attachment generally indicated at 5 is employed. This attachment may be secured to the main typing machine in any suitable manner and in general comprises a pair of oppositely disposed side frames 6 with upwardly extending brackets 7, the latter carrying a shaft 8 on which is mounted one or more rollers 9. There is also a series of rollers provided just above the typing position on which the manifolded paper 10 rests, the latter then passing upwardly around the roller or rollers 9 to the rear of the attachment. The paper is usually fed into the machine from a stack form in which the paper lengths are reversely folded and the paper is held in a flattened condition against the rollers 9 in any suitable manner during the typing operation, after which the paper reverts to its folded state beyond the rollers 9 and is received by a basket in stacked condition. As shown a number of vertically disposed bars 11 may be provided to maintain the flat state of the paper, these bars being secured to a horizontal bar 12 at the top and carrying at the bottom a horizontally disposed guide bar 13 which bears against the paper.

In order to feed the paper upwardly during the line spacing movement and then later during the eject movement, i. e., when the paper is moved quickly and over considerable distance represented by the vertical space between the last typed line of one form and the first typed line of the next form, one or more sprocket chains and sprocket wheels (not shown) are employed. These wheels are mounted on the same shafts as the rollers and the chains carry projections which fit into openings 14 provided on the center line of the paper. The movement of the paper upwardly is controlled automatically by suitable gearing which derives its power from the motor 2 through the control box 3, the operation being such that the paper remains in a stationary position throughout the typing of one line and then is automatically moved upwardly a short distance (the space between lines) ready for the next line to be typed. At the conclusion of the typing of the last line the paper moves quickly upwardly to such a position as to bring the first line to be typed on the next form opposite the typing position.

In order to type or print simultaneously a num-

ber of paper webs, a plurality of carbon ribbons 15 is employed, these ribbons interleaving the webs and caused to move from the right to the left by mechanism which will be described presently. There may also be provided an extra ribbon for the so called "original" or first copy, this ribbon being carried on spool supports 16 which are independent of the supports which carry and guide the carbon paper strips interleaved with the paper webs.

Figures 3 and 4 illustrate ribbon feeding and receiving apparatus which may be employed to advantage in the improved machine. As shown there are four spools (assuming that there are five copies, including the original copy of the paper manifolds to be made) all contained within a cylindrical metal casing 17. The spools are mounted on a shaft 18 and are separated from one another by spacers 19. The innermost spool is separated from the inner side of the casing 17 by a heavy washer 20. The shaft 18 forms an extension of the main shaft 21 which is provided with a shoulder 22 against which the inner side of the casing 17 abuts. The outer end of the shaft portion 18 may be threaded and provided with a nut 23 which serves to hold the spools on the shaft.

It will be understood that, as shown at Figure 1, there are two casings 17, one at each side of the machine and each containing four spools which serve alternately to supply or receive ribbon from the typing position. Each casing 17 is provided at its lower side with slits 24, as many as there are ribbon spools and directly adjacent each slit there is an idler roller 25 secured to the inner surface of the casing, the function of the roller being to guide the ribbon to and from its respective slit. The upper surface of the casing 17 may serve as a support for the side frames 6 to which the brackets 7 may be secured. The casings are supported from the remainder of the side frame structure indicated at 26 of the machine in any suitable and well-known manner, for example, by means of a riveted flanged element 27.

As shown in Figures 2 and 4, the ribbons 15, after leaving the slits 24 of one of the casings 17 passes over a guiding structure, a so-called turn plate generally indicated at 28, then passing along the length of the platen at the typing position after which the ribbons are caused to extend vertically upward over a second turn plate at the opposite side of the machine. The ribbons then enter the slits 24 of the oppositely positioned spool casing 17. As shown in Figure 4 the turn plates 28 comprise an L-shaped member, one leg 29 of which is adapted to bear against the side frame member 26 and the other leg 30 extends in a direction parallel to the axis of the platen. Leg 30 comprises a large rectangular sheet of metal which extends a considerable distance downwardly from the leg 29 and is provided at its lower end with three or more notches indicated at 31 which have diagonal edges.

The arrangement is such that the ribbons 15 move in a vertical direction along the leg or plate 30, the ribbons being separated by the notches 31 and the diagonal edges of which serve to give the ribbons a 90° turn. The turn plate 28 is located directly below the spool casing 17 so that combination of the spools and the diagonal edges provided at the bottom of the turn plates serves rigidly to hold the ribbons in an exact vertical position. After leaving one of the turn plates the ribbon lengths in effect stack

themselves on one another but these lengths are separated by the thickness of each paper web as the ribbons interleave the multiple sheets of paper. After leaving the opposite side of the paper the ribbons are caused to pass around the diagonal edges of a second turn plate 28 which again causes the direction of the ribbons to change 90° and the ribbons are brought into register with the slits 24 of the oppositely positioned spool casing.

It was customary prior to this invention to apply a continuous tension on the ribbons by means of a pin wheel and to feed the ribbons from only one set of spools usually located at the right hand side of the machine, the pin wheel being positioned at the left. The pin wheel was given a rotation through suitable mechanism during the line spacing operation of the machine and was caused to rotate a number of times during the eject operation and at the same time maintaining the ribbon taut and in a stationary position during the typing operation. However, it has been found that under these conditions, and particularly when employing a poorer grade of carbon ribbons, there is a greater tendency for the ribbon to break during any one of the operations of the machine, especially during the eject operation when the paper moves at a fast rate and over a considerable distance in a direction transverse to the direction of the ribbon. Breakage of the ribbon is a serious problem more especially in manifold typing or printing machines in which a number of copies of the printed or typed paper are required.

It will be understood that the friction between the paper ribbon and the paper webs is severe at the typing position due to the tendency of the interleaved elements to pack closely against one another. This packing condition is enhanced when the creases or folds of the manifolded paper which separate the forms from one another pass across the individual ribbons. The horizontal portions of the ribbons are held rigidly in position by the supply spools at one end and the pin wheel at the other end so that there is very little or no opportunity for the ribbons to give in a transverse direction in order to accommodate, at least in part, the vertical longitudinal movement of the paper webs. The carbon ribbons of standard make and which were available on the market prior to the present emergency were usually strong enough to resist any tendency to break, at least during the line spacing operation. Other provisions were usually provided for reducing the breakage tendency during the eject operation of the machine. However, the ribbons which are available on the present market are found to be of inferior quality, having less tensional strength than the earlier forms of ribbon and on occasion the cross-sectional area of each ribbon may vary due to inferior workmanship and other attendant circumstances.

In accordance with my invention, I completely avoid any breakage of the ribbons by providing a ribbon at least twice the width of a normal ribbon and therefore having twice the cross-sectional area with the resulting increased opposition to breakage. In order to render the use of the double width ribbon economically feasible, we have provided means by which the ribbon is theoretically divided into upper and lower portions, each having the same width as the ordinary ribbon and each of these portions are alternately employed in the typing operation.

In carrying out the principles of this inven-

tion we provide means by which the turn plates 28 can be moved upwardly at any desired time in order to bring the lower portion of each ribbon into the typing position. For this purpose each transversely extending leg of the turn plate and which may comprise a flat sheet of metal is provided with a pair of vertically disposed slots 32 which cooperate with outwardly extending bolts 33 secured to the side frames 26. Wing nuts 34 are threaded on the bolts 33, the arrangement being such that the plate 29 of each turn plate 28 can be moved by an operator in a vertical position as guided by the slots 32 and thus move the median line of the ribbon pack 15 upwardly. The effect obtained is illustratively indicated in Figure 5, the upper view of which shows the type impressions 35 at the upper edges of the ribbon while the lower view shows the type impressions near the lower edge of the ribbon when the plates 29 at each side of the machine are raised through an appropriate distance. It will be understood that the removal of one typing level to the other takes place after the complete length of the ribbon has moved once across and between the manifolded forms.

The ribbon may be moved in opposite directions by any suitable mechanism of which one type will now be described.

Ribbon feeding mechanism

Referring more particularly to Figures 2, 3 and 6, the shaft 21 is provided at its middle position with a pair of spaced bevel gears 36, 37 which are keyed or pinned to the shaft. Directly under one of these gears and extending in a vertical direction is a shaft 38 which is pivoted as indicated at 39 to the end section of a power driven shaft 40 provided with a universal joint indicated at 41. The shaft portion 38 is provided with a pair of spaced collars 42 which are positioned on opposite sides of a yoke 43 to which a pull rod 44 is pivotally secured. The rod terminates in a button 45 and is provided with a pair of spaced arcuate notches 46 which cooperate with a curved spring arm 47 which serves as a stop. The rod 44 extends through an opening provided in a panel plate 48 to which is secured a horizontally disposed plate member 49 having a slot 50 which serves to regulate the horizontal or swinging movement of the shaft portion 38. Now assume that the shaft 40 is driven through suitable mechanism or gearing by the motor 2 and that the button 45 is in its fully pulled-out position. The rotary effort of the shaft 40 is transmitted to the bevel gear 36 through a bevel gear 51 which is secured to the shaft portion 52. Thus the shaft 21 (Figure 3) of the ribbon spool mechanism is caused to rotate and let us say in such a direction that the ribbon is caused to be wound on the left hand set of spools and to leave the right hand set of spools as seen in Figure 3. The effect is such that the ribbon is maintained in a taut condition, serving the same function as the pin wheel in the earlier form of machine disclosed hereinbefore. Now assume that the shaft 21 is caused to rotate the proper number of turns only during the line spacing operation and during the eject operation so that the ribbon is caused to remain stationary in its interleaved condition during the time that it takes to type each single line. The ribbon will continue to move during the stated periods and remain stationary during the other periods until the ribbon has been entirely unwound from the right hand series of spools and is now wound completely on

the left hand series of spools. The button 45 is now moved to the right so that the spring arm 47 will contact with the left hand notch 46 causing the bevel gear 51 to swing about its pivot 39 and to mesh with the bevel gear 37.

Under these conditions, when the shaft 40 is caused to rotate, this rotary effort is communicated to the spool shaft 21 in the reverse direction from its previous direction. In other words the 10 ribbon is now caused to be unwound from the left-hand assembly of spools and to be wound on the right hand assembly. The shaft 40 is given a continuous rotation in order that the right hand series of spools will become loaded with ribbon 15 and therefore in the same condition as they were before the spools were unwound during the previous typing operation, leaving just enough ribbon on the left hand series of spools so as to maintain a taut condition of the ribbon. The continuous 20 rotation of the shaft 40 is stopped in any suitable manner and the plates 29 at both sides of the machine are elevated by unloosening the wing nuts 34 and then tightening the same.

The shaft 40 is now given its usual intermittent movement, i. e., a relatively short movement 25 during the line spacing operation and a much longer movement during the eject operation, leaving the ribbon in a stationary condition while the succeeding lines are being typed or printed. 30 The effect of moving the plate 29 upwardly is to bring the lower half portion of the double width ribbon under the type or printing bars as indicated in the lower view of Figure 5 so that in effect fresh surfaces of carbon ribbons are presented to the type bars. After the entire lengths 35 of the ribbons have been exhausted at the end of the second typing operation, rather the second traverse of the ribbons across the paper webs, fresh ribbon is provided by loading the right hand 40 series of spools and threading the ribbon in the usual manner between the sheets of paper and finally catching the left hand end of the ribbons in the left hand spools.

From the foregoing it is evident that while I 45 have provided a so-called double width ribbon in order to take advantage of the greater resistance to breakage due to the larger cross-sectional area of the ribbon, the latter is actually used twice, once at the upper half portion and later at the 50 lower half portion, thus rendering the use of the double width ribbon completely feasible and economical. It has been found that even when employing the poorest grade of carbon paper for the ribbon material the enhanced cross-sectional area brought about by the use of a double width ribbon entirely precludes breakage of the ribbon except under the most unusual circumstances such as if the ribbon were accidentally snagged.

Ribbon-breakage detecting device

In Figure 4 I show apparatus by which the breakage of ribbon can be automatically detected and the machine as a whole brought to a stop without the assistance of the operator. As shown, 60 the front leg 30 of the turn plate 28 is provided with a semi-circular indent indicated at 52 which extends transversely of the plate and has a length comparable to the combined width of the ribbons. There is a rectangular casing 53 projecting outwardly from the front portion 30 of the turn plate, the top and bottom sides of the casing being positioned on opposite sides of the indent 52. The casing is provided at the upper and lower sides with a plurality of slits to receive the separate lengths of the ribbon 15. There

is a flexible member or spring 54 which is riveted to the outermost side of the casing as indicated at 55, this spring having a flattened portion 56 which is adapted to bear against the ribbons as they move through the casing. The contact pressure can be adjusted by means of thumb screw 57 which bears against the spring. The casing 53 is provided with an opening at a position directly opposite the indent 52, this opening being adapted slidably to receive a rod 58 carrying a knob 59 at its inner end which is urged against the ribbon by means of a pressure spring 60. The rod 58 is provided with a flexible strip 61 which carries a contact 62. This contact cooperates with a second contact 63 secured to the casing 53 and which is electrically charged through a wire 64. The latter may be connected to a relay 64a positioned in the energizing circuit of the motor 2 or the wire may be connected directly to an indicating device such as a lamp 64b shown in Fig. 4. It will be understood that there are as many knobs 59 and rods 58 as there are ribbons to be protected.

The switch mechanism may be contained in a protective casing 65 secured to the main casing 53 in any suitable manner. The operation of the ribbon breakage detecting mechanism is readily apparent from the drawings. Should any one of the lengths of ribbon break the knob 59 which bears against that ribbon is permitted to move inwardly into the indent 52 and in so doing, contact is established between the contacts or terminals 62 and 63. This contact may energize an electromagnet or relay (not shown) which is so connected to the armature circuit of the motor 2 as to cause the motor to stop, thus bringing all of the mechanism to a halt. If desired, the closing of the switch at the contacts may additionally or alternately energize a signal light warning the operator who may not be in immediate attendance, of the breakage of at least one of the ribbons. It is apparent that the apparatus as described responds to a change in the tautness of the ribbon so that contact is established at the switch when any condition arises by which the ribbon, at any portion between the winding and unwinding spool becomes loose.

Another way in which the ribbon may be typed thruout its entire width has been illustrated in Figure 7. One or the other of the turn plates 28 (Fig. 2) may be elevated to cause the ribbons to move lengthwise of the platen in a diagonal direction. In Figure 7 the right hand turn plate is assumed to be lifted. It will be noted that the typed characters tend to move from the upper left hand corner of the ribbons to the lower right hand corner. Inasmuch as the ribbons move from right to left during the time spacing operation as explained hereinbefore, every portion of each ribbon is used for impression purposes notwithstanding its considerable width. The same results would be obtained if the ribbons were given a slant with respect to the platen in the opposite direction by elevating the left hand turn plate 28.

Thus, in accordance with my invention I have disclosed not only apparatus by which the tensile strength of the ribbon may be greatly enhanced without affecting its economy of use but in addition a highly efficient and a simple mechanism by which the operator is warned of the breakage of the ribbon or any other unusual condition concerning the ribbon and if desired

the motor may automatically be brought to a stop. The operator would re-thread a new ribbon without any loss in the typing or printing output of the machine.

Having thus fully described my invention what I claim as new and desire to secure by Letters Patent is:

1. A power driven typing machine comprising a platen adapted to receive a sheet of paper, a carbon ribbon supply roll and a carbon ribbon receiving roll located on opposite sides of the platen but out of line therewith, means for guiding the carbon ribbon from the supply roll, along the platen to the receiving roll, said guiding means comprising a pair of turn plates located at opposite ends of the platen, means for exercising a drag on the carbon ribbons, said means including supports secured to said turn plates, a plurality of flexible members carried by said supports and each bearing against a separate ribbon to provide frictional contact, and means also secured to said turn plates subsequent to said flexible member automatically responsive to breakage in a ribbon as it moves from one of said rolls to the other roll across the paper in order to indicate when said breakage occurs, said flexible member and means last named being located side by side and being adapted to move in parallel directions toward each carbon ribbon and on the same side thereof.
2. A power driven typing machine comprising a platen adapted to receive a sheet of paper, a carbon ribbon supply roll and a carbon ribbon receiving roll located on opposite sides of the platen but out of line therewith, means for guiding the carbon ribbon from the supply roll, along the platen to the receiving roll, said guiding means comprising a pair of turn plates located at opposite ends of the platen, means for exercising a drag on the carbon ribbons, said means including supports secured to said turn plates, a flexible member carried by said supports and bearing against the ribbon to provide frictional contact, and means also secured to said turn plates for contacting said ribbon immediately subsequent to said flexible member and responsive to breakage of said ribbon as it moves from one of said rolls to the other roll across the paper whereby said breakage may be indicated, said flexible member and means last named being located side by side and being adapted to move in parallel directions toward each carbon ribbon and on the same side thereof.
